(57) **CLAIM**

The ornamental design for a rocket ball point pen, as shown and described.

DESCRIPTION

FIG. 1 is a perspective view of a rocket ball point pen with the cap member in place showing my new design;

FIG. 2 is a perspective view in an exploded condition;

FIG. 3 is a side elevational view with the cap member removed for ease of illustration, all other side views being identical;

FIG. 4 is a side elevational view of FIG. 1;

FIG. 5 is a top plan view of FIG. 3;

FIG. 6 is a bottom plan view of FIG. 3;

FIG. 7 is a rear elevational view of FIG. 1;

FIG. 8 is a front elevational view of FIG. 1;

FIG. 9 is a bottom plan view of FIG. 1; and,

FIG. 10 is a top plan view of FIG. 1.
